UNITED STATES PATENT OFFICE.

EDWARD H. TATE, OF MALDEN, MASSACHUSETTS, ASSIGNOR TO TATE MANUFACTURING COMPANY, INC., OF BOSTON, MASSACHUSETTS, A CORPORATION OF MASSACHUSETTS.

DUST-MOP.

1,330,502.

Specification of Letters Patent. Patented Feb. 10, 1920.

Original application filed December 16, 1913, Serial No. 807,133. Divided and this application filed December 26, 1916, Serial No. 138,713.

To all whom it may concern:

Be it known that I, EDWARD H. TATE, a citizen of the United States, and a resident of Malden, in the county of Middlesex and State of Massachusetts, have invented an Improvement in Dust-Mops, of which the following description, in connection with the accompanying drawings, is a specification, like characters on the drawings representing like parts.

This invention relates to mops, and more especially to so-called dry mops for dusting floors, walls, ceilings, and furniture.

This is a division of my prior copending application Serial No. 807,133, filed December 16, 1913.

My invention will be best understood by reference to the following description, when taken in connection with the accompanying drawings of one specific embodiment thereof, while its scope will be more particularly pointed out in the appended claims.

In the drawings:

Figure 1 is an elevation of a mop and a mop-holder embodying my invention, showing the mop as it rests upon the floor, and illustrating in full and dotted lines a few of the different positions which the handle is capable of assuming when in use;

Fig. 2 is an elevation of the mop on an enlarged scale as viewed from the left of Fig. 1, showing the handle removed, and the buckle-protecting strap, or shield, unfastened and folded to one side to expose the buckle to view;

Fig. 3 is a plan section on line 3—3 of Fig. 2; and

Fig. 4 is a detail sectional view, on an enlarged scale, on line 4—4 of Fig. 3, illustrating the interengaging relation between the mop and its holder, and also illustrating the socket and stud fastener.

Referring to the drawings, and to the embodiment of my invention which I have selected for illustration, I have there shown a mop of the type commonly called a dry mop. The term "mop" is commonly used to designate the entire device, including its tuft of yarn and its holder and handle, and it is also often used to designate only the tuft of yarn, or cloth, or other material, serving to scrub the surfaces to be cleaned. It will be convenient hereinafter to use the

word in the latter sense, and refer to the mounting of the mop as the mop-holder.

I have herein shown a mop designated generally by the numeral 5, comprising a band 6 of cloth or other material, between the folds of which a bunch or tuft 7 of coarse yarn is inserted, and held by one or more rows of stitches 8. I have herein shown the band 6 wrapped about and encircling a frame 9, which may be and is herein in the form of a ring provided with a shallow circumferential groove 10, in which the band is fitted, as illustrated in Fig. 4. This interengaging relation between the band and the ring prevents the band from accidentally slipping off the ring when in use.

The band may be contracted about the ring by any appropriate means, but herein the terminal portions of the band are adjustably secured to each other by a buckle 11, by means of which the terminal portions may be attached to each other in a plurality of predetermined positions of adjustment. This buckle herein comprises a member 12 provided with a series of apertures 13, to receive a tongue 14 hinged to a member 15. The member 12 is herein secured to one terminal portion of the band by a rivet 16, and the member 15 is herein secured to the other terminal portion by a rivet 17.

As a means for normally holding the tongue in the position illustrated in Figs. 2 and 3, it is herein provided with a short arm 18, having yielding engagement with a spring tongue 19 formed on the member 15. In assembling the mop, the band is wrapped about the ring, and the tongue 14 inserted in the proper aperture 13, so that when the tongue is swung toward the position shown in Figs. 2 and 3, it will draw the terminal portions of the band toward each other, and cause the band closely to hug the ring. In fact, by this means, the band can be contracted so as to cause the same to enter the circumferential groove 10, and thus interengage with the ring to lock the band against accidental removal.

As a means for protecting the buckle, so that it shall not become accidentally opened by engagement with furniture, and so that it shall not scratch furniture and other surfaces with which it may come in contact,

I have herein provided a shield in the form of a strap 20, having one end secured at 21 to one terminal portion of the band 6. This strap extends across the outer face of the 5 buckle thus wholly covering the latter, and at its other end is secured to the other terminal portion of the band by any suitable detachable fastening means, as for example a familiar form of socket and stud fas- 10 tener, comprising a socket member 22 and a stud member 23, one of which is secured to the strap or shield, and the other to the terminal portion of the band.

In practice, the length of the strap is such 15 that it must be stretched somewhat, before it can be fastened, and will then hug the face of the buckle and the terminal portions of the band 6, although for the sake of clearness in the drawings, an actual separation 20 of a considerable space is shown. In addition to preventing interference of the buckle with furniture and other objects, the strap 20 serves as a supplementary fastening for the terminal portions of the band 6, and, in 25 fact, might be wholly substituted for the buckle if desired, although the construction shown is preferred.

The mop is herein provided with a handle 24, which may be attached to the ring 9 in 30 any appropriate manner, but herein is threaded into a socket 25, provided in a member 26 located within, and having opposite terminal portions abutting against, opposite sides of the inner circumference of 35 the ring. The member 26 is herein pivoted to the ring by providing the latter with opposite perforations 27-27, to receive screws 28-28 threaded into said member, said screws serving not only as pivots, but as ad- 40 justable means for applying variable frictional resistance to turning movement of the handle about its pivotal axis. To this end, the screws are provided with heads, herein countersunk into the perforations 27, 45 these heads being preferably so thin as to occupy but little space in the circumferential groove 10. By simply turning these screws in the proper direction, the frictional resistance to turning movement of the handle may 50 be varied, and by this means, the required resistance to prevent the holder from swinging too freely on its handle is supplied. If desired, the screws may be tightened to such an extent as to secure the member 26 rigidly 55 in any desired position of adjustment.

When the mop is in use, this is an im- 60 portant consideration, because as the mop is passed back and forth across a surface and meets with unexpected resistance, the mop and its holding ring will not suddenly turn over, as might otherwise be the case. In practice, the frictional resistance is so ad- 65 justed that the mop will readily accommo- date itself to changes in angular relation between the handle and the surface being

cleaned, yet without requiring careful at- 70 tention on the part of the user to prevent the mop from turning over on its side, instead of remaining flatwise on the surface being cleaned.

It will now be apparent that, by grasping the handle, the user may place the mop upon the floor, wall, ceiling, or other surface, whether it be in a horizontal or vertical plane, or upon the upper or lower side of 75 any object, such as furniture, and that the pivotal attachment of the mop to its handle is such that the mop may accommodate it- 80 self to the varying positions in which it is placed, and will remain flat against the sur- face at all times when it is in use. It will also be evident that, regardless of the height of the user, or the angular position in which the handle is held, or other variations in 85 conditions of use, the mop will at all times automatically accommodate itself to such changes, without any special attention on the part of the user. One important ad- 90 vantage is that the handle may be removed, and the member 26 grasped and utilized as 95 a handle, by means of which the mop may be manipulated. When so used, the user's thumb and fingers will, of course, extend down into the space within the ring, and in a most convenient manner. When used in 95 this fashion, also, the mop will accommo- date itself to the surface being cleaned, even though the member 26 be firmly grasped in the hand of the user.

When the mop is to be cleaned, it can be 100 detached from its holder by simply unfas- tening the protecting strap within the buckle, and finally unwrapping the mop from the ring, and after being cleaned, it can be instantly and conveniently returned 105 to its place by a reversal of the foregoing operation, without the use of any tools.

While I have herein shown and described one specific embodiment of my invention for 110 illustrative purposes, and have disclosed and discussed in detail the construction and ar- 115 rangement incidental to one specific applica- tion thereof, it is to be understood that the invention is limited neither to the mere de- tails or relative arrangement of parts, nor to its specific embodiment herein shown, but 120 that extensive deviations from the illustrated form or embodiment of the invention may be made, without departing from the prin- ciples thereof.

Having thus described my invention, what I claim and desire by Letters Patent to se- 125 cure is:-

1. The combination with a mop, of a mop holder comprising a frame to which said mop is attached, swinging manipulating means located within and having opposite terminal portions abutting against opposite sides of the inner surface of said frame, and adjustable screw means to resist turning 130

- movement of said manipulating means with relation to said frame.
2. The combination with a mop, of a mop holder comprising an open frame to which said mop is attached, a member spanning the opening in said frame, and fastening means extending from said frame into opposite ends, respectively, of said member to hold the latter in place in said frame.
- 10 3. The combination with a mop, of a mop holder comprising an open frame to which said mop is attached, a member spanning the opening in said frame, and pivots extending from said frame into opposite ends, respectively, of said member.
- 15 4. The combination with a mop, of a mop holder comprising an open frame about which said mop is disposed and to which said mop is attached, a member extending across the opening in said frame and having its opposite ends abutting against inner surfaces of said frame, and fastening means extending through said frame into said ends of said member.
- 20 5. The combination with a mop, of a mop holder comprising an open frame about which said mop is disposed and to which said mop is attached, manipulating means extending across the opening in said frame and having opposite ends abutting against inner surfaces of said frame, and pivot means extending from said manipulating means through said frame, said pivot means comprising screws equipped with pressure-adjusting devices operating axially against said frame.
- 25 6. The combination with a mop, of a mop holder comprising an open frame about which said mop is wrapped, a handle having a part located within and having opposite terminal portions abutting against opposite sides of the inside of said frame, and pivots extending through said opposite sides of said frame and into said handle part.
- 30 7. The combination with a mop, of a mop holder comprising an open frame provided with an external groove and about which said mop is wrapped, a handle having a part located within and having opposite terminal portions abutting against opposite sides of the inside of said frame, and fastening elements provided with heads disposed in said groove and with shanks extending through said opposite sides of said
- frame into said opposite terminal portions of said handle part.
8. The combination with a mop, of a mop holder comprising an open frame provided with an external groove and about which said mop is wrapped, a handle having a part located within and having opposite terminal portions abutting against opposite sides of the inside of said frame, and pivots provided with heads disposed in said groove and with shanks journaled in said opposite sides of said frame and extending into said opposite terminal portions of said handle part.
- 15 9. The combination with a mop, of a mop holder comprising an open frame provided with an external groove and about which said mop is wrapped, a handle having a part located within and having opposite terminal portions abutting against opposite sides of the inside of said frame, and pivot members provided with heads disposed in said groove and with shanks journaled in said opposite sides of said frame and extending into said opposite terminal portions of said handle part, at least one of said shanks being threaded into said handle part for applying an adjustable frictional resistance to turning movement of said members about their pivotal axis.
- 20 10. A cleaning implement comprising, in combination, a mop, and a mop holder comprising a frame about which said mop is wrapped, a bar disposed across and within said frame and having opposite terminal portions adjacent opposite sides of said frame, and trunnions extending from said bar through said opposite sides of said frame and provided with means adjustably to resist turning movement of said bar with relation to said frame.
- 25 11. A mop holder comprising an open frame about which the mop may be secured, said frame consisting of a band whose inner edge defines an opening extending through said frame, a member spanning the opening in said frame and attached to said frame at a plurality of points, and a handle-receiving socket intermediate such points of attachment.
- 30 In testimony whereof, I have signed my name to this specification.

EDWARD H. TATE.
